UNITED STATES PATENT OFFICE.

FRANK L. AUEROCKS, OF BENSON, NEBRASKA.

SORTING-RACK FOR ROUGH-DRY LAUNDRY.

1,306,297.

Specification of Letters Patent. Patented June 10, 1919.

Application filed April 28, 1916. Serial No. 94,282.

To all whom it may concern:

Be it known that I, FRANK L. AUEROCKS, a citizen of the United States, and a resident of Benson, in the county of Douglas and 5 State of Nebraska, have invented certain new and useful Improvements in Sorting-Racks for Rough-Dry Laundry, of which the following is a specification.

My invention relates to racks or supports 10 for detachably sustaining articles of clothing and the like in definitely-assorted groups, and is particularly intended to facilitate the sorting and checking of laundryed articles while in a rough-dry condition. It is the object of my invention to provide in a device for this purpose, a plurality of closely-spaced inclined supporting-arms adapted to be engaged by ordinary marking-pins to sustain the articles attached to said 15 pins; to provide means for separately designating the several arms, said means being arranged so that the identifying marks are positioned immediately adjacent to the ends of the several arms, and so that the member 20 on which the identifying marks are placed forms a guard for said ends of the arms; to provide a supporting frame for said arms, from which they may be readily removed to facilitate the removal of articles hanging 25 thereon; to provide means for quickly reversing the position of the supporting frame so that one side thereof may be utilized for arms on which articles are being sorted, while the other side carries arms from which 30 the articles are being removed and checked; to provide means by which the guard for the ends of the arms may be reversed in position so as to dispose it at either side of the support; and to provide various other novel and 35 useful constructions and combinations of parts for simplifying and expediting the work in connection with which the device is used, as will be more fully set forth herein-after.

In the accompanying drawings Figure 1 is a perspective view of a rack embodying my invention, Fig. 2 is a detail transverse section showing one of the rack-arms and the socket and guard-plate therefor, Fig. 3 40 is a side view of one of the number-pins used in connection with the rack, Fig. 4 is a detail vertical section through one of the heads for the arm-supporting cross-bar, Fig. 5 is a diagrammatic perspective view of a pair of 45 the racks arranged for joint use, Fig. 6 is a plan view of one of the racks, Fig. 7 is a de-

tail side view of the displaceable pivoting means for the rack, Fig. 8 is a detail transverse section of the same on the plane of the line 8—8 of Fig. 7, and Fig. 9 is a detail end 60 view of the pivoting device in another position.

In the illustrated and preferred embodiment of my invention I provide a main frame consisting principally of pieces of 65 metal pipe or tubing suitably connected by appropriate angular fittings. At each end of the frame there are two rounded or globular foot-pieces 30 which are connected by elbows 31 with a horizontal piece 32 having 70 a T-fitting 33 at the center thereof, from which a standard 34 extends up vertically. The fittings 33 have side-openings in which are secured the ends of a horizontal bottom-rod 35. The upper ends of the standards 34 75 have spherical heads 36 secured thereon, and beneath said heads there is slidably fitted on each standard a T-head 37 provided with a set-screw 38 by which it may be secured in adjusted positions on the standard. To the 80 heads 37 are secured the ends of a tubular cross-bar 39 which extends horizontally between the heads, as shown. Upon the cross-bar 39 there are fitted a plurality of socket-pieces each comprising a collar-portion 40 85 having a set-screw 41 by which it is secured on the cross-rod, and having a laterally extending portion 42 provided at its inner end with a rectangular recess which is continued in the outer portion as a narrow rectangular 90 vertically-extending channel or groove. The socket-portions 42 are arranged to extend alternately on opposite sides of the cross-bar 39 and are upwardly inclined therefrom, as shown. The rack-arms 43 are made from 95 flat rectangular metal bars, of which one edge is beveled off at each end, the pointed ends thus formed being slightly rounded, as shown. In the pointed portions at each end of the bar small transverse openings 44 are 100 made, for a purpose hereinafter set forth. The arms are interchangeable and reversible, and either end thereof may be inserted into the sockets, resting therein as shown in Fig. 2. The arms are easily removable from the 105 sockets by first slightly lifting the outer ends and then sliding them outwardly from the sockets. When properly seated in the sockets, however, the arms are firmly held therein and have no tendency to become displaced therefrom. The pointing of the ends 110 of the arms facilitates their removal from

the sockets and their insertion therein, as well as making it easier to pass the outer ends through the marking-pins which are hung thereon, and on account of the reversibility and interchangeability of the arms the operation of placing them in the sockets is greatly expedited.

On each of the standards 34 above the heads 37 there are collars 45 which rest upon the upper ends of said heads and are revoluble about the standards. From said collars 45 integral arms 46 extend diagonally outward and upward, approximately parallel with the arms 43, and at their outer ends said arms 46 have vertical portions which fit revolvably in sockets therefor in the ends of a flat bar or plate 47.

The length of said plate, between the centers of the end-sockets for the arms 46, is the same as the distance between the standards 34, so that by swinging the arms about the vertical axes of the standards, as indicated by the arrows in Fig. 6, the plate may be positioned alternatively at opposite sides of the frame, being held slightly above and beyond the pointed outer ends of the arms 43. When the plate is so positioned it forms a guard or shield for said pointed ends of the rack-arms, and also provides a surface on which may be marked numbers or other indicia for separately designating each of the adjacent rack-arms. For convenience in marking such indicia upon the plate 47, the surface thereof is preferably slated or coated with a composition on which marks may be made with chalk or the like, in contrasting color, and readily erased when it is desired to change the numbers or other markings. The height at which the arms 43 and plate 47 are held, may be varied as desired by adjusting the heads 37 vertically upon the standards 34, thus raising or lowering the cross-bar 39, and also the collars 45 and arm 46 which carry the guard-plate.

At the center of the bottom-rod 35 a sleeve 48 is secured thereon, and from said sleeve an integral stem or leg 49 extends downward so as to be normally quite near to but not in contact with the floor on which the foot-pieces 30 are resting. A shallow metal dish or concavo-convex plate 50 is provided, having in the center of the concave side thereof a recess 51 adapted to receive the end of the leg 49. The dish 50 is loosely connected with the sleeve 48 by means of two chains 52 of which the ends are connected with eyes 53 and 54 on the sleeve and at the edges of the dish, the chains being of such length that when the dish is suspended therefrom it will hang beneath the leg 49 in spaced relation thereto, as shown in Fig. 9. The dish 50 normally rests on the floor at one side of the leg, as shown in Figs. 1 and 8, but may be caused to swing in beneath the leg, as in Fig. 9, by lifting one end of the

frame and thus raising the leg to such a position as is shown in the latter figure. Then, upon lowering the frame, the end of the leg is seated in the recess 51 as shown in Fig. 7, and is thus held in a slightly elevated position so that most of the weight of the frame will be carried thereon, the frame assuming a slightly inclined position with the foot-pieces at one end resting on the floor, and those at the other end raised above the floor. By then slightly lifting the lower end of the frame, or pressing down upon the raised end thereof, the frame will be substantially balanced upon the dish, and while so balanced it may be easily rotated about a vertical axis passing through the leg and dish. After rotating the frame to any desired position, the leg may be disengaged from the dish by lifting one end of the frame enough to raise the leg above the marginal portion of the dish, and then swinging the dish to one side, or by moving the frame laterally far enough to displace the leg from above the dish, while the latter remains in fixed position upon the floor.

From the foregoing, the structure and a part of the operation of the rack will be clearly apparent, but in order to fully perceive the operative utility of the device it is necessary to consider briefly the particular conditions under which it is especially adapted to be used.

It is becoming a common practice for laundries throughout the country to do a great deal of so-called rough-dry work, the same taking the place of the usual domestic laundrying, the laundry ironing only the "flat pieces," and returning the miscellaneous articles of clothing, etc., dry and starched but un-ironed. It is also a common practice, with the miscellaneous articles of rough-dry work, to mark the same for identification and sorting in the laundry, by means of numbered pins, instead of stamping the separate articles with initials, numbers or other permanently-affixed marks. The work is handled in batches or "loads," a load being usually the amount collected by a wagon in one trip, and consisting of from fifteen to thirty "bundles" each belonging to different persons. A characteristic form of the numbered pins, above mentioned, is shown in Fig. 3 of the drawings, and such pins are provided in sets of thirty or more, each pin of a set having the same number stamped or otherwise marked thereon, and each set of the pins being kept normally in a tray or the like having separate sockets or compartments for each pin. Each bundle of a load is assigned a certain number, and each of the several articles of a bundle has attached thereto one of the pins of the set bearing the number designating such bundle. Each load is handled as a unit throughout the various laundrying operations, so that at

the completion of the washing and drying operations the several articles comprised within the load, sometimes several hundred different articles, are mixed up indiscriminately and must be sorted into bundles, according to the identification of the pieces afforded by the number-pins attached thereto.

Now, in the use of my invention, it is preferable to employ two of the racks 10 jointly, arranging the same in an angular or V-shaped position with respect to each other, as indicated in Fig. 5, the basket or receptacle, containing the pieces to be sorted, being placed in proximity to the spaced ends 15 of the racks, or at the third side of the triangular space between the racks. The guard-plates 47 are turned to the adjacent sides of the two racks, and on said plates there is marked with chalk or the like the 20 numbers corresponding to the pins with which the pieces of the several bundles of the load are marked, each of the several numbers on the plates 47 being placed in proximity to the outer pointed end of one 25 of the arms 43. As the workman or "sorter" removes the several pieces from the receptacle containing them, the pin on each piece is located and said pin is then passed onto the rack-arm designated by the corresponding 30 number on the plate 47. As the sorting is continued and the arms become filled, the pieces hanging therefrom will overlap each other more or less owing to the proximity of the arms to each other, but the 35 length of the arms is made such that, allowing for the overlapping of the adjacent pieces, each arm will carry as many pieces as are contained in an ordinary bundle. As the number-pins are placed on the arms 40 they slide to the lower or inner ends thereof, owing to the inclined position of the same. When the racks are employed as above described, only those arms on the adjacent sides of the two racks are used to receive the sorted pieces, and it is unnecessary 45 for the workman to take more than one step away from the receptacle in order to reach and place a piece upon any of the rack-arms. After the sorting of a load has 50 been completed the position of the racks may be reversed, employing the pivotal supporting means afforded by the leg 49 and dish 50, to sustain the racks while they are being turned around. The arms containing 55 the assorted pieces are thus disposed on the outer or remote sides of the racks, while at the inner or adjacent sides the other sets of arms may be placed in the sockets therefor, the plates 47 swung around to positions 60 joining the pointed ends of said arms, and marked with numbers corresponding to the pins of another load of articles to be sorted. The sorting of a second load may then proceed as before, and while this is being done 65 another workman may be removing the pre-

viously assorted pieces from the outer sides of the racks, without interfering with the work of the sorter.

The removal of the assorted articles is most conveniently effected by removing the 70 arms from the sockets, one arm at a time being taken out while the several pieces of a bundle are hanging thereon. When removing the loaded arms from the sockets, one of the number-pins may be passed through 75 each of the perforations 44 in the ends of the arms, to prevent the other pins from sliding off said ends. As each of the loaded arms is removed from the rack it is carried to a checking-table, and while still held on 80 the arm the pins are counted to verify the number of pieces in the bundle. The pins are then removed from the arm, and finally from the pieces to which they are attached, and the pieces wrapped into a bundle ready 85 for delivery.

From the foregoing it will be apparent that my invention provides a means for simplifying and greatly expediting the work of sorting rough-dry laundry articles, enabling the sorting to be done in a very small space, and the work of the sorter to be continued substantially without interruption, since the sorted bundles may be removed and checked by another workman, 95 after the reversal of the racks, without interfering with the work of the sorter.

Now, having described my invention, what I claim and desire to secure by Letters Patent is:

1. In a laundry-sorting apparatus, a rack having at the opposite sides thereof a series of detachable arms, a guard-plate adapted to extend adjacent to the ends of said arms and to receive erasable indicia for separately designating the several arms of the series, and detachable means for supporting the rack pivotally upon a vertical axis, whereby the 100 rack may be swung about said axis to present its opposite sides to a fixed point. 110

2. A sorting-rack for rough-dry laundry, comprising a movable frame having spaced vertical standards, a cross-bar connected with said standards and vertically adjustable thereon, a series of socket-pieces secured on said cross-bar and having recessed portions extending laterally therefrom, upwardly inclined arms removably seated in said recessed portions of the socket-pieces, a guard-plate positioned adjacent to the outer ends of said arms, and means supported on the ends of the cross-bar for sustaining said guard-plate so that the same will partake of vertical adjustments of the 115 cross-bar. 120

3. A sorting-rack for rough-dry laundry, comprising a frame having spaced vertical standards, a horizontal cross-bar having its ends adjustably secured to said standards, series of upwardly inclined rack-arms de- 130

- tachably connected with said cross-bar and extending from opposite sides thereof, arms pivoted on the standards above the ends of the cross-bar, and a plate pivotally connected with the ends of said arms and movable by rotation of said arms about the standards from a position adjoining the ends of one series of the rack-arms to a like position with respect to the opposite series.
- 5 4. In a sorting-rack for rough-dry laundry, a frame having series of rack-arms extending from opposite sides thereof, spaced foot-portions normally supporting said frame, a leg arranged symmetrically of the frame and centrally of said foot-portions, and a part loosely connected with the frame and movable to a position beneath said leg to support the same at a raised position, whereby the frame may be balanced on said 10 leg and moved pivotally about a vertical axis passing through the same.
- 15 5. In a sorting-rack for rough-dry laundry, a frame having a horizontal cross-bar, two series of rack-arms extending from op-
- posite sides of said cross-bar, a guard-plate 25 adapted to extend adjacent to the ends of said rack-arms, means pivoted adjacent to the ends of the cross-bar for supporting said guard-plate whereby the same may be moved into position adjacent to either series of the 30 rack-arms, and detachable means for pivotally supporting the frame whereby the same may be rotated about a vertical axis to reverse the position thereof.
6. In a sorting-rack for rough-dry laundry, a frame having a horizontal vertically-adjustable portion, a series of socket-pieces secured on said horizontal portion and having parallel recessed laterally extending portions, pointed arms detachably seated in 35 said recessed portions and extending diagonally upward from the horizontal frame-portion, said arms being perforate adjacent to the ends thereof, and a plate spaced slightly from the outer ends of the arms and 40 adapted to receive indicia for separately designating the adjacent arms.
